Atty's:

UNITED STATES PATENT OFFICE.

JOHN C. HACKETT, OF ST. LOUIS, MISSOURI.

LIFTING-JACK.

SPECIFICATION forming part of Letters Patent No. 604,583, dated May 24, 1898.

Application filed July 19, 1897. Serial No. 645,094. (No model.)

To all whom it may concern:

Be it known that I, JOHN C. HACKETT, of the city of St. Louis, State of Missouri, have invented certain new and useful Improvements in Lifting-Jacks, of which the following is a full, clear, and exact description, reference being had to the accompanying drawings, forming a part thereof.

My invention relates to lifting-jacks; and it consists of the novel construction, combination, and arrangement of parts hereinafter shown, described, and claimed.

Figure 1 is a side elevation of my improved lifting-jack with the hand-lever elevated. Fig. 2 is a horizontal section taken approximately on the line 2 2 of Fig. 1. Fig. 3 is a vertical section taken approximately on the line 3 3 of Fig. 2 with the hand-lever depressed. Fig. 4 is a view in perspective of a lifting-plate. Fig. 5 is a view in perspective of the overbalanced pivoted fulcrum.

Referring to the drawings by numerals, 6 is the toothed post.

15 15 is the sliding block mounted upon the post 6 and carrying the lifting-plate 7.

8 is the hand-lever for operating the lifting-plate.

9 is the overbalanced pivoted fulcrum which forms a connection between the hand-lever 30 and the toothed post, and 10 is the locking-link which holds the lifting-plate in its elevated position.

The toothed post 6 projects upwardly from the center of the horizontal base-plate 11, and 35 the post is T-shaped in cross-section, its first and second flanges forming the flat front face 12 and its third flange projecting backwardly from the junction of the first and second flanges, the rear edge of said third flange being notched to form the upwardly-projecting teeth 13. The projection 14 extends straight up from the upper end of the post in alignment with the face 12 at the time the casting is made, but after the parts are put together 40 said projection is bent forwardly to form a stop to limit the upward movement of the sliding block 15 and to hold the parts from being disconnected. The sliding block 15 has a T-slot 16 formed from its rear face to receive the toothed post 6. The lifting-plate 7 is rectangular in plan and is formed integral with the block 15. The trunnions 17 and 18

are formed integral with the block 15 and extend from opposite sides of said block in alignment with each other. A bracket-shaped 55 web 19 extends downwardly from the center of the plate 7, the rear edge of said web engaging the face 12 of the toothed post, as required, to form a brace to strengthen and support the plate 7. The lifting-plate is 60 placed in position with the toothed post 6 in the T-slot 16 and the plate in front of the post before the projection 14 is bent, thus forming a sliding connection between the plate and the post.

65 The hand-lever 8 consists of the bar 20 and the arms 21 and 22, formed integral with the forward end of said bar. When the lever 8 is cast and before the parts are put together, the arms 21 and 22 are spread apart at their free ends, as required, to allow the block 15 and the trunnions 17 and 18 to be inserted between the arms of said forward end, and bearings 23 and 24 are formed in the forward ends of said arms to receive said trunnions 70 17 and 18. The arms 21 and 22 are slightly curved upwardly as they extend forwardly from the bar 20, and bearings 25 and 26 are formed horizontally through said arms a short distance back of the bearings 23 and 24.

75 80 The overbalanced pivoted fulcrum 9 consists of the curved plates 27 and 28, mounted in parallel positions and connected by the fulcrum-bar 29 and the weight 30. The trunnions 31 and 32 extend in horizontal alignment outwardly from the plates 27 and 28 and approximately at the centers of the plates. The lug 33 extends outwardly from near the lower end of the plate 27. The overbalanced pivoted fulcrum 9, constructed as described, 90 is placed between the arms 21 and 22, and then said arms are bent toward each other until the trunnions 31 and 32 enter the bearings 25 and 26 and the trunnions 17 and 18 enter the bearings 23 and 24.

95 The locking-link 10 consists of the V-shaped bar 34, having the bearings 35 and 36 formed upon its ends. When constructed, the V-shaped bar 34 is spread apart at its ends to allow of the links being placed in position 100 above the arms 21 and 22 and with the bearings 35 and 36 at opposite ends of the trunnions 17 and 18. Then the ends of the bar are bent toward each other until said trun-

nions 17 and 18 enter said bearings 35 and 36. After the parts have been put together as described it is obvious that they cannot be taken apart without bending or breaking 5 some of the parts.

The forward end of the arm 21 will engage the lug 33 when the rear end of the bar 20 is elevated to nearly a vertical position. The weight 30 overbalancing the fulcrum-bar 29 10 operates to hold the fulcrum-bar yieldingly in engagement with the teeth 13. When it is desired to lift a load, the post is placed in position, with the plate 7 under the load and with the plate 11 resting upon a suitable foundation. Then the hand-lever 8 is elevated bodily until the lifting-plate 7 is brought into engagement with the load. Then the free end of the bar 20 is depressed, the overbalanced pivoted fulcrum engages one of the 15 teeth 13, and the lifting-plate 7 is elevated, thus lifting the load. When it is desired to elevate the load but a short distance, one depression of the hand-lever is sufficient. Then the link 10 is swung forwardly until its central portion engages one of the teeth 13, as 20 shown in dotted lines in Fig. 3, and the jack is locked to hold the load in its elevated position.

If it is desired to lift the load farther than 25 can be accomplished by one depression of the hand-lever 8, then the locking-link is manually engaged and held yieldingly in engagement with the teeth 13, and by successively operating the hand-lever the lifting- 30 plate will be elevated step by step, the load being held by the link 10, engaging one of the teeth 13, while the fulcrum is being elevated to the next higher one of the teeth 13. When the hand-lever 8 is elevated to a vertical 35 position, the end of the arm 21 engages the lug 33 to swing the fulcrum-bar 29 out of engagement with the teeth 13 and then the lifting-plate and hand-lever may readily be raised or lowered to any desired position upon 40 the post.

I claim—

1. In a lifting-jack, the toothed post 6; said post being T-shaped in cross-section, its first and second flanges forming the flat front face 50 12 and its third flange projecting backwardly from the junction of said first and second flanges, the rear edge of said third flange being notched to form the upwardly-projecting teeth 13, the sliding block 15 having the T-slot 16 formed from its rear face, said toothed post 6 being mounted in said slot, the lifting-plate 7 projecting forwardly from said sliding block, the trunnions 17 and 18 extending from opposite sides of said block 15 in alignment with each other, the bracket-shaped web 19 extending downwardly from the center of said plate 7 with its rear edge engaging the face 12 of the toothed post, a hand-lever having bearings to receive said trunnions 60 65 and a fulcrum carried by said hand-lever to engage said teeth, substantially as specified.

2. In a lifting-jack, the toothed post 6; said toothed post being T-shaped in cross-section, its first and second flanges forming the flat front face 70 12 and its third flange projecting backwardly from the junction of the first and second flanges and the rear edge of said third flange being notched to form the upwardly-projecting teeth 13, the projection 14 formed integral with the toothed post 6 and designed to be bent forwardly after the parts of the jack have been assembled, the block 15 having the T-slot 16 in its rear face, said toothed post being mounted in said T-slot, said block being provided with the lifting-plate 7, the 80 trunnions 17 and 18 and the bracket-shaped web 19 for strengthening the plate 7, a hand-lever having bearings in which said trunnions operate, a fulcrum attached to said hand-lever and engaging said teeth, and a locking-link 85 having bearings to receive said trunnions and extending upwardly and backwardly in position to engage said teeth, substantially as specified.

3. In a lifting-jack, a T-shaped toothed post 90 having upwardly-projecting teeth formed upon the edge of its third flange, a sliding block having a T-slot to receive said toothed post as required to form a sliding connection between the block and the post, a lifting- 95 plate projecting forwardly from said block, trunnions projecting from opposite sides of said sliding block, the hand-lever 8 having bearings in which said trunnions operate; said hand-lever consisting of the bar 20 and the arms 21 and 22 formed integral with the forward end of said bar, said arms 21 and 22 having bearings in their forward ends to receive said trunnions and the forward ends of said arms being spread apart to allow of the 100 insertion of said trunnions and then bent toward each other to hold the trunnions in position and the bearings 25 and 26 formed in said arms 21 and 22 a short distance back 105 of the bearings in which said trunnions operate; the overbalanced pivoted fulcrum 9 mounted between said arms 21 and 22 and engaging the teeth of said post; said overbalanced pivoted fulcrum consisting of the curved plates 27 and 28 in parallel positions 110 and connected by the fulcrum-bar 29 and the weight 30, the trunnions 31 and 32 extending in a horizontal line outwardly from said plates 27 and 28 and approximately at the centers of the plates and engaging in said bearings 115 25 and 26, substantially as specified.

4. In a lifting-jack, a toothed post, said toothed post being T-shaped in cross-section and having upwardly-projecting teeth formed upon the edge of its third flange, a sliding 120 125 block having a T-slot in its rear face in which said toothed post operates, a lifting-plate projecting forwardly from said block, trunnions projecting from said sliding block, a hand-lever having its forward end bifurcated and 130 having bearings in the forward ends of the arms forming the bifurcated portion to re-

ceive said trunnions, the overbalanced pivoted fulcrum 9 mounted between the arms of said hand-lever and in position to engage said teeth; said fulcrum 9 consisting of the 5 curved plates 27 and 28 in parallel positions and connected by the fulcrum-bar 29 and the weight 30, the trunnions 31 and 32 extending outwardly from the centers of said plates 27 and 28 into bearings in said arms of said 10 hand-lever and the lug 33 extending out-

wardly from near the lower end of one of said curved plates and in position to be engaged by the end of one of said arms of said hand-lever, substantially as specified.

In testimony whereof I affix my signature 15 in presence of two witnesses.

JOHN C. HACKETT.
